UNITED STATES PATENT OFFICE.

JACOB DELONG, OF COVERT, NEW YORK.

IMPROVEMENT IN HARROWS.

Specification forming part of Letters Patent No. **36,644**, dated October 14, 1862.

To all whom it may concern:

Be it known that I, JACOB DELONG, of Covert, in the county of Seneca and State of New York, have invented a new and Improved Harrow; and I do hereby declare that the following is a full, clear, and exact description of the same, reference being had to the accompanying drawings, making a part of this specification, in which—

Figure 1 is a plan or top view of my invention. Fig. 2 is a side view of the same.

Similar letters of reference indicate corresponding parts in the two figures.

The object of this invention is to obtain a jointed or flexible harrow of simple construction, and which will be strong and durable, with its teeth well braced, and so arranged or fitted in or to the harrow as not only to be permanently secured in position, but also made to serve as a means to firmly connect the framing of the harrow together, or keep the parts thereof in a proper relative position with each other.

To enable those skilled in the art to fully understand and construct my invention, I will proceed to describe it.

The frame of the harrow is constructed of wrought-metal bars $a a'$, of flat form, and so placed or disposed as to cross each other at right angles, as shown clearly in Fig. 1.

I design to construct the harrow of two equal parts, $A A'$, and connect the same together by means of hinges or joints formed by bending the contiguous ends of the bars a in a vertical position, having them lap a certain distance, as shown at a^x , and perforated to admit of a rod or shaft, B, passing through them, on which the bars a may work or play freely. By this means simple and durable joints or hinges are obtained, the ends of the rod or shaft B being headed to prevent its casual withdrawal from the bars a .

C represents the teeth of the harrow. These are of quadrilateral form, pointed at their lower ends, and pass through holes made in the bars $a a'$, where they cross each other. The teeth are fitted in metal sockets D at their upper parts above the bars $a a'$. These sockets are of oblong form, and provided at their centers with a head, b, which serves to firmly support the teeth. The teeth also pass through similar sockets, E, which are underneath the bars

$a a'$, and are precisely similar in construction to the sockets D, being provided with heads e, which also serve to support the teeth C. The sockets D are in line with the sockets E, and they have an angular or oblique position with the bars $a a'$, as shown in Fig. 1, the ends of the sockets projecting over or beyond the angles formed by the intersection of the bars $a a'$. The upper and lower sockets, D E, are connected together by screws or screw-bolts d, which fit snugly in the angles of the bars and serve as braces for the same to retain them in proper position or prevent any lateral working. The sockets also serve as clamps to keep the surfaces of the bars $a a'$, where they cross each other, in close contact.

The clamps may be of wrought or cast iron. Malleable cast-iron would answer a good purpose. I do not, however, confine myself to any particular material. If necessary, the teeth may be secured in the upper sockets, D, by means of pins passing horizontally into the upper sockets or heads thereof and into the teeth, and also into the lower sockets, E.

By constructing the harrow in this way it is rendered extremely strong, light, and durable, and may be manufactured at a moderate cost, there being but little for the mechanic to do, except the mere assembling of the parts and adjusting them together, as the parts may be obtained or be all furnished ready to be secured together.

The bars $a a'$ may be of any desired thickness and width, according to the size of the harrow.

Having thus described my invention, what I claim as new, and desire to secure by Letters Patent, is—

The bars $a a'$, arranged or disposed so as to cross each other at right angles, in combination with the teeth C and sockets D E, the teeth passing through the sockets and bars, and the sockets adjusted to the bars and made to clamp the same by means of the screws or bolts d, which fit in the angles of the bars, substantially as and for the purpose herein set forth.

JACOB DELONG.
